**REFINING OF HYDROCARBON OILS
WITH HF AND TIF**

Arthur P. Lien, Highland, Ind., and David A. McCaulay, Chicago, Ill., assignors to Standard Oil Company, Chicago, Ill., a corporation of Indiana

Application August 30, 1952, Serial No. 307,192

20 Claims. (Cl. 196—39)

This invention relates to the refining of mixed hydrocarbon oils. More particularly, it relates to the refining of hydrocarbon oils containing, in addition to other hydrocarbon compounds, aromatics, organic sulfur compounds, oxygenated compounds and nitrogen compounds. The invention is of particular interest to the treatment of hydrocarbon distillates boiling in the naphtha range in order to recover therefrom benzene, toluene, C₈ aromatic hydrocarbons, and higher boiling aromatic hydrocarbons.

Naturally occurring hydrocarbon oils are mixtures of various classes of hydrocarbons and various organic compounds containing one or more of the elements sulfur, oxygen and nitrogen. For some uses many hydrocarbon oils contain an objectionable amount of aromatic hydrocarbons, e. g., diesel oils, kerosenes, domestic fuel oils and lubricating oils. For some uses hydrocarbon oils should not only be low in aromatics, but also low in organic sulfur compounds. In some cases such as coal tar distillate, the oil contains substantially only aromatics and some organic sulfur compounds, and it is desired to remove the sulfur compounds only. In the case of shale oil, it is desirable to remove not only sulfur compounds, but also nitrogen compounds and oxygen compounds. One of the better methods for refining of a mixed hydrocarbon oil containing objectionable amounts of aromatic hydrocarbons and organic sulfur compounds is to treat with liquid hydrogen fluoride containing boron trifluoride. The HF—BF₃ treating agent acts very much like a selective solvent. However, this process has the serious disadvantage of having to operate at high pressures when temperatures above ambient are used because the BF₃ is a very volatile gas. Another method for improving the quality of heavy hydrocarbon oils such as lubricating oils is by treatment with liquid HF and silver fluoride as disclosed in U. S. 2,531,723.

Aromatic hydrocarbons exist in virtually all crude oils. The separation by fractional distillation of these aromatics from the non-aromatics, i. e., paraffins, naphthenes, organic sulfur compounds and—in the case of naphthas derived from thermal or catalytic cracking operations—olefins and oxygenated compounds such as alkylphenols, is extremely difficult because members of the various classes of hydrocarbons have similar boiling points. The solvent extraction processes for improving the quality of lubricating oil fractions are not suitable for the recovery of aromatics boiling in the naphtha range. While liquid SO₂ extraction has been adapted to benzene and toluene recovery, it suffers from the disabilities of operating at rather low temperature and relatively low percentage recovery. Now in commercial use are processes using extractive distillation or azeotropic distillation for the recovery of the aromatic hydrocarbons boiling in the naphtha boiling range, i. e., benzene, toluene, ethylbenzene and the xylenes. These processes all possess certain disabilities ranging from low percentage recovery to an inability to recover more than one substantially pure aromatic constituent in a given integrated process.

2

It is an object of this invention to refine mixed hydrocarbon oils by an extraction method. Another object is the removal of aromatic hydrocarbons, organic sulfur compounds and phenolic compounds from hydrocarbon oils containing objectionable amounts of these materials. A further object is the refining of lubricating oil distillates to improve the viscosity index thereof. Still another object is the recovery of aromatic hydrocarbons from hydrocarbon mixtures boiling in the naphtha range, i. e., below about 450° F. A particular object of this invention is the treatment of an aromatic-containing naphtha which boils below about 325° F. to obtain the aromatic hydrocarbon portion thereof substantially free of interfering non-aromatic materials in order that individual aromatic compounds or close-boiling groups of compounds may be recovered therefrom. Further objects will become apparent in the detailed description of the invention.

It has been discovered that the objects of this invention can be attained by treating hydrocarbon oils which contain appreciable amounts of aromatic hydrocarbons, and/or organic sulfur compounds, and/or phenolic compounds, and/or nitrogen compounds by treating said hydrocarbon oils with thallium monofluoride—TIF—in the presence of a sufficient amount of substantially anhydrous liquid HF to form a separate HF-rich phase.

TIF is a crystalline solid having a boiling point of 570° F. It has been discovered that the solubility of TIF in liquid HF is enormously increased when an aromatic hydrocarbon, organic sulfur compound, or phenolic compound is brought into contact with the TIF, in the presence of liquid HF. For example, a mixture of solid TIF and liquid HF is rapidly converted to a clear, homogeneous liquid when the mixture is contacted with a sufficient amount of benzene or xylene.

The solubility of lower molecular weight mononuclear aromatic hydrocarbons in liquid HF at ambient temperatures is quite low, e. g., at 70° F., benzene and xylene are soluble to the extent of 3 volume percent. It has been discovered that more of these aromatic hydrocarbons can be taken up by liquid HF in the presence of TIF than the liquid HF is capable of dissolving in the absence of TIF. It is believed that this increase in solubility is due to the formation of a complex consisting of the aromatic hydrocarbon, HF and TIF. (Aromatic hydrocarbons and TIF do not form a complex in the absence of liquid HF). This complex is extremely soluble in liquid HF and it is possible to have enormously more TIF and aromatic hydrocarbon present in a complex-liquid HF solution than liquid HF alone is capable of dissolving. This complex is stable in the presence of liquid HF at ambient temperatures. However, the components of the aromatic hydrocarbon complex can be recovered readily by distilling the HF and the aromatic hydrocarbon whereupon the TIF remains behind in the form of a very finely divided solid.

Within the limits of experimental error it has been found that 1 mol of TIF and 1 mol of aromatic hydrocarbon such as benzene, toluene, xylene or ethylbenzene are present in each mol of TIF-aromatic-HF complex. The exact content of HF is unknown, but is believed to be 1 mol per mol of complex.

It has been found that when a mixture of aromatic hydrocarbons—such as benzene, toluene, xylene and ethylbenzene—and non-aromatic hydrocarbons is treated with a solution of TIF in liquid HF, an upper raffinate phase and a lower extract phase is obtained. The upper raffinate phase consists of a very small amount of liquid HF and a mixture of hydrocarbons, which mixture contains a smaller percentage of aromatics than the feed mixture. The extract phase consists of liquid HF, complex, and physically dissolved aromatic and non-aromatic hydrocarbons; the extracted hydrocarbons recovered from

the liquid HF-TIF treating agent consist predominantly of aromatics—usually the extracted hydrocarbons will contain substantially less than 10% of non-aromatic hydrocarbons.

The percentage recovery, in a single contacting stage, of the aromatic hydrocarbons present in the feed mixture is dependent upon the amount of TIF present in the treating agent. It has been found that 70 to 75 volume percent of the aromatics in the feed can be readily extracted by using 1 mol of TIF for each mol of aromatic to be recovered. The use of the theoretical amount of 1 mol of TIF for each mol of aromatic in the feed mixture will not remove more than 80 to 85% of the total aromatics therein, in a single contacting stage. When very high percentage recoveries are desired of the aromatic hydrocarbons contained in a hydrocarbon distillate boiling in the naphtha range, the maximum amount of TIF should be used; this amount corresponds to 1 mol per mol of aromatic hydrocarbons in the feed plus the amount of TIF that can be physically dissolved by the complex containing liquid HF. It is preferred to operate with an amount of TIF somewhat less than that amount which results in the formation of a separate solid TIF phase as no beneficial results are obtained by the presence of the solid TIF, and serious operational difficulties may result.

The amount of TIF used will depend on the amount of aromatic extraction desired. When treating naphthas the amount of TIF may be as little as 0.1 mol per mol of aromatic hydrocarbon in the feed. It is preferred to speak of the usage of TIF in terms of mols per mol of aromatic hydrocarbon that is to be extracted, i. e., when less than the maximum amount of extraction is desired.

Some gain in extraction efficiency is obtainable by the use of continuous countercurrent contacting or batch multi-stage contacting. Normally a single contacting stage provided with adequate mixing produces results that are almost as good as those obtained with multi-stage contacting. When using single-stage contacting for maximum extraction of aromatic hydrocarbons, the maximum amount of TIF should be used.

It is necessary to have present in the treating zone an amount of liquid HF sufficient to participate in the formation of the TIF containing complex, i. e., 1 mol per mol of TIF present. In addition to this amount it is necessary to have additional liquid HF present in order to dissolve the complex that has been formed and to permit the separation of the complex as the solution in the liquid HF. Of course sufficient liquid HF must be present to produce a separate liquid HF-rich extract phase. The extract phase consists of complex, aromatic hydrocarbons and nonaromatic hydrocarbons in simple solution and excess HF. Although the minimum amount of liquid HF needed depends somewhat on the amount of aromatic hydrocarbon that is to be extracted from a mixed hydrocarbon feed, it has been found that phase separation can be obtained when using as little as 10 volume percent of liquid HF, based on total feed. Larger amounts of liquid HF up to 1500 volume percent or more, based on feed, may be used. It is preferred to use between about 100 and 500 volume percent of liquid HF, based on feed.

It has been found that the presence of water has a detrimental effect on the process of this invention. The process should be carried out under substantially anhydrous conditions and the liquid HF used should be substantially anhydrous, i. e., the liquid HF should not contain more than 2 or 3% of water.

Non-aromatic hydrocarbons are only very slightly soluble in liquid HF; they are somewhat more soluble in liquid HF containing the aromatic-TIF-HF complex. Apparently the complex solubilizes both aromatic hydrocarbons and non-aromatic hydrocarbons so that more of these hydrocarbons can be taken up by the liquid HF than would be predicted by the solubility of the hydrocarbons in pure liquid HF. However, this solubilizing effect at constant TIF level appears to be a function of

the concentration of the complex in the liquid HF because, surprisingly enough, it has been discovered that the amount of non-aromatic hydrocarbon present in the extract hydrocarbons is lower at large liquid HF usage than at small liquid HF usage. The amount of non-aromatics present in the extract hydrocarbons at the same TIF concentration can be reduced to an ordinarily unobjectionable amount of 2-3% in a single stage by using about 300% or more of liquid HF based on total feed.

Temperatures as low as -60° F. may be used if the resultant increase in viscosity is not considered to be disadvantageous. At higher temperatures, e. g., 250-300° F., the HF catalyzes the isomerization and even cracking of the paraffins and naphthenes normally present in naphthas derived from petroleum sources. In general temperatures are maintained between about 0° and 160° F. and it is preferred to operate at ambient temperatures, i. e., between 30° and about 100° F. In order to keep the HF in the liquid state, sufficient pressure must be maintained on the extraction system to ensure this condition at the temperature of operation; e. g., at 160° F., about 100 p. s. i. g.

For best results the feed stock and the solvent should be contacted for a time long enough to permit maximum recovery of aromatics by the particular amount of TIF present in the treating agent. The length of time needed for this amount of contacting in large part will depend upon the efficiency of the contacting device. When operating at ambient temperatures, contacting times in excess of the minimum necessary for desired amount of recovery are not harmful. In general it has been found that with efficient mixing, good results can be obtained at contact times between about five minutes and six hours.

Organic-sulfur compounds, such as are normally present in most petroleum naphthas, form complexes with TIF in the presence of liquid HF. These complexes appear to be more difficult to decompose than the TIF aromatic complexes. However, the complex can be dissociated by heating to a temperature on the order of 400-500° F. These sulfur-compound complexes appear to emulsify liquid HF and the hydrocarbons, making phase separation very difficult and, in some cases, gravity separation alone is not sufficient. The larger the amount of sulfur in the naphtha to be treated, the more likely it is that separation difficulties will be encountered. In general it is preferred to operate on hydrocarbon mixtures which contain essentially no sulfur compounds—on the order of less than .02 wt. percent sulfur. Naphthas containing a sulfur content suitable for this process can be readily obtained by treating high sulfur naphthas with liquid HF or by hydrodesulfurization or by hydroforming or by any other process that removes sulfur without simultaneously removing appreciable quantities of the desired aromatics.

In general olefins, in the amounts usually present in naphthas that would be desirable feed stocks to this process, do not interfere with separation of the extract phase from the raffinate phase. It has been found that the aromatic compounds present are alkylated by the olefins in the feed stock to form alkylaromatics which complex with TIF and which are recovered in the extract phase along with the non-alkylated aromatics. These alkylated aromatics boil above xylenes and can be readily separated from xylenes by simple fractional distillation. No appreciable formation of alkylfluorides has been observed when treating olefin-containing feed stock. Thus the disadvantage for operation on an olefin-containing feed stock is the loss of some of the more desirable aromatic compounds to higher boiling alkylaromatics. However, these alkylaromatics have high octane numbers and can be used as aviation safety fuel blending stocks; or they may be used as high solvency naphthas.

The phenolic-type materials found in most naphthas derived from thermal or catalytic cracking react with TIF to form complexes which are detrimental to phase

separation. Also, these materials increase the difficulty of obtaining pure compounds by simple fractional distillation from the aromatics recovered by our process. However, one or two washes with a concentrated sodium hydroxide solution will reduce these phenolic compounds to a level where no appreciable hindrance to phase separation will take place. Another method of removing these phenolic bodies is to treat the raw naphtha with liquid HF.

This process may be applied to a mixture of hydrocarbons comprising aromatics, paraffins, naphthenes and olefins which boil in the naphtha range, i. e., below about 450° F. The presence of polyalkylbenzenes and polynuclear aromatics in hydrocarbon distillates boiling above about 450° F. renders very difficult the recovery of individual compounds or a group containing a small number of compounds boiling close together. The feed stock to this process must be free from H₂S and substantially free of organic sulfur compounds, particularly those found in virgin naphthas derived from high sulfur crudes, such as West Texas crude. It is preferred that the feed stock contain less than about 0.02 wt. percent of sulfur. In general it has been found that a high sulfur naphtha which has been desulfurized by treatment with liquid HF is a satisfactory feed to our process. Naphthas containing appreciable amounts of materials boiling above 450° F. are more difficult to desulfurize by conventional methods to a level at which the sulfur compounds will not interfere with the separation of the feed stock into a raffinate phase and an extract phase. Naphthas boiling below about 325° F. are particularly suitable for this process because they are easily desulfurized and dephenolized and substantially pure C₆, C₇ and mixed C₈ aromatics are readily recovered therefrom.

A particularly suitable feed for this process is the naphtha derived from the so-called hydroforming process, i. e., the vapor phase treatment of a virgin naphtha at 850–1050° F. in the presence of hydrogen over a catalyst such as molybdena on an alumina support or a platinum-containing catalyst. The hydroformate from such a process is low enough in sulfur to permit operation without further desulfurization and is so low in olefin that very little of the benzene, toluene and xylenes is degraded to higher boiling alkyl aromatics by alkylation.

By suitable pretreatment to remove interfering materials, this process for recovering high purity aromatic hydrocarbons can utilize naphthas boiling below about 450° F., and particularly those boiling below 325° F., derived from distillation of petroleum, the thermal or catalytic cracking of naphthas from petroleum, naphthas derived by the hydroforming or hydrodesulfurization of virgin or cracked naphthas, or a mixture of aromatics, paraffins, naphthenes and olefins derived from any source.

The usual naphtha feed stock to this process will contain 50 volume percent or more of non-aromatic material. Where aromatic concentrates are available from super fractionation equipment, feed stock containing 70 or 80% of benzene or toluene or C₈ aromatics may be available. It has been found that when operating on feed stocks containing much in excess of 50% of aromatic hydrocarbons, it is desirable to add a diluent to the feed stock prior to the contacting step. The diluent should be a paraffinic and/or naphthenic hydrocarbon or a mixture of hydrocarbons that is low in materials that would interfere with phase separation and that will be readily separable by simple fractional distillation from the individual aromatic hydrocarbons. It is preferred to use as diluents paraffinic and naphthenic hydrocarbons of low boiling point since these materials are not isomerized or cracked by the liquid HF at the preferred operating temperatures. Suitable hydrocarbons are pentane, hexane, heptane, cyclohexane, methylcyclohexane, petroleum ether, etc. When operating at low temperatures such as 30° F. the diluents might be higher boiling paraffinic or naphthenic hydrocarbons containing 9, 10 or 11 carbon atoms. However, in general, the feed stocks to this proc-

ess will not require the use of a diluent. It is preferred to operate without diluent since the presence of high percentages of non-aromatic compounds requires the use of more TIF in order to obtain the same percentage extraction and more HF in order to maintain selectivity of extraction.

The non-aromatic hydrocarbons extracted from the feed by the treating agent boil in about the same range as the aromatic hydrocarbons. Their presence decreases the purity of the aromatic hydrocarbons and they must be removed in order to obtain substantially pure aromatics as the final product. It has been found that these non-aromatic hydrocarbons can be readily displaced from the extract phase by washing the extract phase with a diluent type hydrocarbon such as pentane, hexane or a 9, 10 or 11 carbon atom hydrocarbon. A single stage washing operation is usually sufficient to reduce the non-aromatic content of the extract phase to a point where nitration grade benzene or toluene can be made by simple fractional distillation of the recovered aromatic hydrocarbons.

It has further been discovered that the use of liquid HF—TIF treating agent markedly improves certain qualities of hydrocarbon oils boiling in the heavier-than-gasoline range, i. e., from about 350° to about 700° F. The treatment is particularly effective in improving the burning quality of kerosenes and cetane number of diesel fuels when the raw oils contain objectionable amounts of aromatic hydrocarbons. Also, this treatment markedly improves the viscosity index of lubricating oils derived from naphthenic-type and asphaltic-type crudes.

It is believed that this quality improvement is obtained through the formation of a liquid HF-soluble complex of TIF and HF with the objectionable aromatic hydrocarbons, organic sulfur compounds and nitrogen compounds.

Some improvement in quality of the oil can be obtained by using even a trace amount of TIF and further improvements can be obtained by increasing the amount of TIF until substantially all the materials removable by the liquid HF—TIF treating agent have been removed. In general the larger the amount of extractable materials present, the more TIF needed in the treatment. The upper limit on TIF usage is readily determined by the fact that when a solid TIF phase appears, no further improvement is obtainable. By the time that this third phase of solid TIF appears, a sufficiently refined oil has been attained. Thus there can be used between a trace amount of TIF and an amount of TIF that will not dissolve completely into the extract phase. Expressing the TIF usage in another way, we can use from 0.1 wt. per cent to about 25 wt. per cent and, in some cases to about 100 wt. per cent, based on the raw oil. The amount of TIF needed to obtain a particular degree of refinement is readily determinable by small scale treatment of samples of the raw oil.

When treating the heavy distillates sufficient liquid HF must be present in the extraction zone to form a separate HF-rich phase, i. e., extract phase. The minimum amount of liquid HF needed will vary somewhat with the type of oil being treated and the extractable materials content of the raw oil. The viscosity of the raw oil affects phase separation and, in general, the more viscous the raw oil, the more HF needed to obtain good phase separation. The presence of extractable materials in the liquid HF increases the viscosity of the extract phase so that good phase separation may be difficult when treating raw oils containing large amounts of extractable materials with small amounts of HF. When treating light gas oils the minimum HF usage may be as low as 10 volume percent, based on the raw oil. When treating lube stocks such as distillate for the production of S. A. E. 20 oil, as much as 20 volume percent of liquid HF may be needed to obtain good phase separation. It is preferred to use more than the bare minimum amount of liquid HF.

As much as 1500 volume percent liquid HF has been used without detrimental effect. However, little significant gain in refinement is obtained by using very large amounts of liquid HF. For most raw oils satisfactory phase separation and a satisfactory degree of refinement can be obtained by using from about 10 to about 500 volume percent of liquid HF. It is preferred to use between about 30 and 300 volume percent.

In the treatment of heavy distillates viscosity has an appreciable effect on the cleanliness of the phase separation; the viscosity of the heavy distillate can be reduced by adding an inert diluent thereto. The diluent should be relatively inert to the solvent action of the treating agent and also to the catalytic action of the treating agent. Additionally, the diluent should be readily separable by distillation from the refined oil, although in some cases it may be desirable to leave the diluent in the refined oil. Suitable diluents are pentane, hexane, petroleum ether, cyclohexane, various naphtha fractions low in extractable materials, etc. Materials such as heptane or octane can be used when the treating is at about ambient temperatures. However, diluents containing about 6 or more carbon atoms are readily isomerized and even cracked by our treating agent at temperatures above about 250° F., so that their use at elevated temperatures is undesirable. In general olefinic hydrocarbons are not suitable diluents. The amount of diluent used will be dependent upon the type of raw oil being charged, but in general will be between about 10 and 200 volume percent based on raw oil. When using a diluent it may be possible to reduce the amount of liquid HF ordinarily used and still obtain a satisfactory phase separation.

When treating heavy distillates the temperature of treatment may be on the order of those used when treating naphthas. However, in the case of lubricating oils, some improvement in quality can be obtained by operating at temperatures as high as 450-500° F. The HF catalyzed, isomerization, alkylation, cracking and other reactions result in an increase in the amount of liquid HF-soluble material and an improved quality raffinate oil. The lower temperatures of operation should be above the freezing point of the heavy distillate itself or the freezing point of the diluted feed. In general it is preferred to treat heavy distillates at temperatures between about 50° and 100° F.

Contacting time will be dependent on the type of raw oil, the amount of liquid HF-TIF treating agent and the temperature of operation. In general times between about 5 minutes and 60 minutes in each extraction stage will be sufficient to obtain the desired degree of refining.

The heavy distillate feed to the liquid HF-TIF treating operation can be: various fractions obtained from the distillation of crude oil, e. g., kerosenes, heater oil, lube oils, etc., or the crude oil itself, or reduced crudes. Another class of materials suitable as a feed may be oils derived from the treatment of the above materials, e. g., raffinates and extracts from the solvent treatment of kerosenes or lube oils. Shale oil, and its various fractions, is a suitable feed to our process. The liquid products from the hydrogenation of coal or the Fischer-Tropsch process are suitable feeds to our process. Appreciable amounts of olefins can be eliminated from olefin-containing feeds by treatment with liquid HF-TIF; the alkylate may or may not be extracted into the extract phase. In general oils containing large amounts of olefins are not a desirable feed to our process. In general the most suitable feed stocks are petroleum distillates boiling in the heavier-than-gasoline range, i. e., above about 350° F. and below about 700° F., and particularly those distillates derived from high sulfur and high aromatic content crudes, such as, West Texas crude, Winkler crude, etc.

The raffinate phase from the treating of hydrocarbon oils with liquid HF-TIF treating agent will usually contain some dissolved liquid HF and also some entrained HF; small amounts of solid TIF may also be entrained.

The TIF can be recovered by filtration, by a coalescing operation or in some cases by distilling the raffinate oil. The liquid HF is readily removed from the raffinate phase by distillation at temperatures of about 100° F., at atmospheric pressure. In some cases the raffinate may contain minor amounts of alkyl fluorides; these can be readily removed by percolation through bauxite.

The extract phase obtained from the treatment of hydrocarbon oils with liquid HF-TIF treating agent is readily decomposed by treatment with water, preferably cold water or ice; the upper layer of extract oil can be decanted from the lower aqueous layer. The extract oil contains the extracted materials, i. e., hydrocarbons and/or organic sulfur compounds. The lower aqueous layer consists of a mixture of hydrofluoric acid and TIF. The extract oil can be freed of traces of HF by treatment with dilute caustic. This method is particularly suitable for laboratory operations.

It is preferred to decompose the extract phase as follows: The extract phase is placed in a vessel, usually provided with a few fractionation trays, wherein the temperature of the extract phase is raised until the HF vaporizes and passes out of the vessel. The top temperature in the decomposing vessel is held at about the boiling point of HF in order to prevent the removal of extract materials along with the HF. In the bottom of the decomposer after the removal of HF, there exists a slurry of extract materials and solid finely divided TIF. This slurry is passed to a filter which retains the solid TIF. The TIF can be reused in the process. In the case of lower boiling extract materials, the extract materials may be distilled leaving behind the solid TIF. By operating under vacuum, the HF may be removed at low temperatures. It is preferred to operate at from about 200° to 500° F.; the lowest possible temperature is preferred because of the side-reactions resulting from the catalytic action of the treating agent. Where it is desired to avoid side-reactions in the extract phase, the decomposer may be operated under vacuum in order to remove a major part of the liquid HF at temperatures below about 100° F.; then the partially denuded extract phase is heated to from about 200° to 500° F. to remove the remainder of the HF.

Normally the raffinate from the heavy distillate treatment process will be the desired product. However, the low sulfur, low aromatic content thereof makes the refined oil a very suitable feed to a catalytic cracking operation; thus our process may be used to treat cycle gas oils which are low quality catalytic cracking feeds in order to improve their suitability for catalytic cracking. These cycle oils may be derived from thermal cracking; coking or catalytic cracking.

It has been found that the organic sulfur compounds present in the extract from the treatment of heavy naphtha and gas oils boiling between about 350° and 600° F. are very readily catalytically cracked to produce a high octane, low sulfur product. Particularly good results are obtained when the extract is fractionated and that portion boiling below about 450° F. is charged to the catalytic cracking operation.

It has also been discovered that a separation can be made between ethylbenzene and xylene by the treatment of a mixture of ethylbenzene and xylene, e. g., a mixed C₈ aromatic hydrocarbon fraction with liquid HF-TIF treating agent. It has been found that by contacting said mixture with an amount of TIF of about 1 mol per mol of xylene present therein, and sufficient liquid HF to participate in the complex and also to dissolve said complex to form a separate extract phase, a raffinate phase and an extract phase are formed. The mol ratio of ethylbenzene/xylene in the raffinate is higher than the ratio in the feed. By the use of multi-stage contacting, it is possible to produce a high purity ethylbenzene raffinate product and a high purity xylene extract product.

It has also been discovered that a more economical separation of ethylbenzene from xylene can be obtained by

extractive distillation procedure. In this procedure the feed mixture of ethylbenzene and xylene is introduced at about the vertical mid-point of a fractionation column and liquid HF—TIF agent introduced at a higher point in said column. Temperature and pressure are so regulated in the column that there is withdrawn overhead a stream of HF vapor and aromatic hydrocarbon vapor. The aromatic hydrocarbon vapor is cooled to form a high purity ethylbenzene fraction. From the bottom of the tower is withdrawn a mixture of high purity xylene and solid TIF, which mixture may be readily separated by filtration. In the extractive distillation operation, about 1 mol of TIF is used per mol of xylene.

The results obtainable by this process in the separation of lower molecular weight mononuclear aromatics from naphthas is illustrated by the following example: In this example the contacting was carried out in a carbon steel reactor equipped with a 1725 R. P. M. stirrer. An amount of solid thallium formate was introduced into the reactor and an excess of liquid HF over the stoichiometric quantity was introduced. A reaction occurred at room temperature as evidenced by increase of pressure in the reactor. When the reaction had stopped as evidenced by constant pressure in the reactor, the formic acid and excess HF were pumped out of the reactor leaving behind solid thallium monofluoride. The feed to the example consisted of a synthetic blend of 60 volume percent n-heptane, 20 volume percent m-xylene and 20 volume percent of p-xylene. The mol ratio of xylene to thallium was 2.3. An amount of liquid HF equal to 120 volume percent on total feed was introduced into the reactor and then the feed was introduced therein. The liquid HF—TIF feed mixture was agitated at about 50° F. for 60 minutes. The contents of the reactor were then permitted to settle for 10 minutes before being withdrawn.

The lower extract phase was withdrawn into a vessel containing crushed ice; the hydrocarbons from the decomposed extract phase were decanted away from the aqueous layer. These hydrocarbons were washed with caustic to eliminate traces of HF and then were distilled in a 30-plate laboratory column to obtain narrow boiling fractions. In this example only one narrow boiling fraction was obtained. The raffinate phase was washed with aqueous caustic to remove entrained HF and was then distilled to obtain a single narrow boiling fraction. The purity and the compositions of these fractions were determined by a combination of infrared analysis, boiling point, specific gravity and refractive index.

Analysis of the raffinate and extract phase showed that 64 mol percent of the aromatics present in the feed had been extracted into the extract phase. This corresponds to xylene/TIF mol ratio of 1.29. The apparent ability of the TIF to extract more than an equal molar amount of xylene is due to the solubilizing effect of the complex on the ability of liquid HF to dissolve aromatic hydrocarbons.

Within the limits of experimental error the molar distribution of m-xylene and p-xylene in the raffinate and in the extract was unchanged over that of the feed xylenes.

The annexed drawing which forms a part of this specification shows an illustrative embodiment of one method of utilizing this process. This embodiment illustrates the extraction of benzene, toluene and Cs aromatic hydrocarbons from a hydroformate naphtha boiling below about 325° F. It is to be understood that many pieces of process equipment such as pumps and valves have been omitted from this embodiment. These pieces of equipment may readily be added thereto by those skilled in the art.

The feed to the embodiment consists of a debutanized hydroformate having an end point of 325° F. This hydroformate contains about 55% of benzene, toluene and Cs aromatics, about 3% of olefins and about 0.01 wt. percent sulfur.

The feed from source 11 passes through line 12 into mixer 13. In mixer 13 the feed is thoroughly contacted

with the extract phase from a previous contacting step to be described later; this extract phase—consisting of liquid HF, complex, an excess of soluble TIF and dissolved non-aromatic hydrocarbons—is passed into line 12 by way of line 14. Mixer 13 is provided with a heat exchanger 16 which permits the temperature of contacting to be maintained at the desired point. In this illustration contacting is carried out at 75° F. and at about 25 p. s. i. g. for about 15 minutes.

From mixer 13 the mixed feed-solvent passes through line 17 into settler 18. In settler 18 the mixed feed-solvent separates into a raffinate phase consisting mainly of non-aromatic hydrocarbons and a small percentage of aromatic hydrocarbons and an extract phase consisting of liquid HF, complex, excess soluble TIF and minor amounts of non-aromatic hydrocarbons. The raffinate from settler 18 is withdrawn through line 19 and is passed into line 21.

Liquid HF from source 22 is passed through line 23 into vessel 24 where it meets TIF from source 26 and line 27 and also recycled liquid HF—TIF mixture. In order to recover the aromatics present in the feed in the least number of stages we use 1.2 mols of TIF in this particular illustration, all of which will be present in mixer 31. The liquid HF must be present in an amount great enough to form the complex and to dissolve the complex once formed. More than this amount is desirable as phase separation and aromatic selectivity are facilitated by a larger volume of liquid HF. In this particular illustration we use 300 volume percent of liquid HF based upon the feed stock charged to the process.

The liquid HF—TIF mixture from vessel 24 passes into line 21 where it meets the raffinate phase from settler 18 and on into mixer 31. Mixer 31 is provided with a heat exchanger 32 for control of the temperature of contacting; herein we operate at about 75° F., the same as that used in the first contacting stage in mixer 13. The liquid HF—TIF treating agent and the first raffinate phase are intimately contacted for about 15 minutes in mixer 31.

From mixer 31 the mixture passes through line 33 into settler 34. In settler 34 a second raffinate phase containing little or no aromatic hydrocarbons is separated from the extract phase. This second raffinate phase from settler 34 passes through line 36 into stripper 37 which is provided with reboiler 38. In stripper 37 the HF dissolved in the second raffinate phase is removed overhead through line 39; stripper 37 may be operated at about 200° to 400° F. at about 25 to 150 p. s. i. g. In heat exchanger 41 the HF is condensed to a liquid and may be recycled to the process through line 42. Some low boiling material may azeotrope with the HF and this may be recycled along with the HF. However, if this material is not wanted in the extraction step, it can be removed by a settling operation (not shown) from the liquid HF and sent to the non-aromatic product. The non-aromatic portion of the feed stock passes out of stripper 37 through line 46 to storage not shown. These non-aromatic hydrocarbons are almost entirely isoparaffins of high octane number and are valuable as gasoline blending material.

The very slight fluoride content thereof can be eliminated by percolation through bauxite.

From settler 34 the extract phase is sent to the first contacting stage through line 14. By this two-stage countercurrent contacting procedure, we are able to recover substantially all the aromatic hydrocarbons present in the feed stock.

From settler 18 the extract phase is passed through line 51 into line 52 where it meets pentane from source 53. From line 52 the extract phase-pentane mixture passes into mixer 54. The pentane usage will be dependent upon the percent of non-aromatics in the extract phase. We have found that particularly good results are obtained when between 50 and 200 volume percent based on total hydrocarbons present in the extract phase is used. From mixer 54 the pentane-extract phase mixture passes through line 56 into settler 57. From settler 57 a raffinate phase

11

consisting of pentane and substantially all the non-aromatics present in the extract phase from line 51 is withdrawn by line 58. The material in line 58 may be withdrawn from the system through valved line 59 or a portion may be recycled to the washing step through valved line 61 and line 52. In order to avoid a buildup of interfering non-aromatic hydrocarbons in the washed extract phase, we prefer that the contaminated pentane be discarded to gasoline blending stock.

From settler 57 the washed extract phase passes through line 66 through heat exchanger 67 and line 68 into vessel 69. Vessel 69, commonly called a decomposer, is provided with a heat exchanger 71 and a number of bubble trays in order to obtain some fractionation. In decomposer 69 the HF and pentane are passed overhead through line 74 and are condensed by heat exchanger 75. The HF-pentane mixture passes from line 76 into settler 77 where two phases are formed. The upper pentane layer passes out through line 78 to gasoline blending stock. The lower HF layer passes out of settler 77 through line 79. The decomposer 69 is maintained at a top temperature below the boiling point of benzene in order to keep all the aromatics in the liquid state in decomposer 69. We have found that a suitable top temperature for the operation of decomposer 69 is between about 100 and 140° F., at atmospheric pressure operation. Higher temperatures may be used if the decomposer is operated at super atmospheric pressure. The bottom temperature of decomposer 69 can be between 200 and 500° F. and about the mid-boiling point of the aromatics is a suitable temperature.

In the bottom of decomposer 69 a slurry of solid, finely divided TIF and aromatic hydrocarbons is formed. This slurry passes out of decomposer 69 through valved line 81 into filter 82. Filter 82 may be any type which can be made of liquid HF-resistant materials and HF-vapor tight, and which is able to retain finely divided solids. In this flow sheet we show only one filter. However, normally two or more filters will be used in order to permit continuous operation and the presence of additional filters is to be understood in this particular illustration of our process. Filter 82 retains the solid TIF and the aromatics pass out through valved line 83.

Liquid HF from settler 77 passes through valved line 79 into filter 82; the TIF in the filter is removed by the liquid HF and the liquid HF-TIF mixtures passes out of filter 82 through valved line 86 and is recycled to vessel 24 through line 87.

From filter 82 the aromatics pass through valved line 83, through heat exchanger 91 and through line 92 into fractionator 93, which fractionator is equipped with reboiler 94. In fractionator 93 nitration-grade benzene is taken overhead through line 97 to storage not shown. The remaining aromatics pass out of the bottom of the fractionator 93 through line 99, heat exchanger 101 and line 102 into fractionator 103.

Fractionator 103, equipped with reboiler 104, separates the aromatics from line 102 into a nitration-grade toluene fraction, taken overhead through line 106 to storage not shown; and a bottoms fraction consisting of C₈ aromatics and higher boiling polyalkyl aromatics.

The bottoms from fractionator 103 pass out through line 107, heat exchanger 108 and line 109 into fractionator 111, which is equipped with reboiler 112. The C₈ aromatics, consisting of o-xylene, m-xylene, p-xylene and ethylbenzene pass out of fractionator 111 through line 114 to storage not shown. From the bottom of fractionator 111 through line 116 higher boiling polyalkyl aromatics are withdrawn. These higher boiling aromatics were formed by the alkylation of lower boiling aromatics with the olefins present in the feed by the catalytic action of the liquid HF.

This embodiment of our invention shows how simply we are able to separate benzene, toluene and C₈ aromatics from a mixed hydrocarbon and by simple fractional dis-

12

tilation recover nitration-grade benzene and toluene and mixed C₈ aromatic hydrocarbons separately.

When it is desired to recover aromatic hydrocarbons from naphthas containing substantial amounts of sulfur, e. g., 0.1 or more, the feed naphtha should be given a desulfurization treatment prior to contacting with liquid HF-TIF treating agent. Many desulfurization methods are known. However, it is preferred to use the method of U. S. 2,450,588. Very briefly, this method involves the treatment of naphtha with liquid HF at ambient temperatures to produce a low sulfur raffinate product and a high sulfur HF extract phase. This raffinate product is suitable for treatment in the process of this invention.

Thus having described the invention, what is claimed is:

1. A process for refining a mixed hydrocarbon oil, which process comprises contacting said oil with TIF in the presence of sufficient liquid HF to form an extract phase and separating a raffinate phase from said extract phase.
2. The process of claim 1 wherein said contacting is carried out at a temperature below about 500° F.
3. The process of claim 1 wherein said contacting is carried out in the presence of an inert diluent.
4. A process for the treatment of a hydrocarbon oil which contains extractable materials, which process comprises contacting said oil at a temperature below about 500° F. with an effective amount of TIF in the presence of sufficient liquid HF to form an extract phase and separating a raffinate phase from said extract phase.
5. The process of claim 4 wherein in said contacting step said liquid HF is present in an amount from 10 to 1500 volume percent based on said oil and said TIF is present in an amount from at least some to about the limit of solubility of TIF in said extract phase.
6. The process of claim 5 wherein said temperature is less than about 200° F.
7. The process of claim 4 wherein said extractable materials are selected from the group consisting of mono-nuclear aromatics, polynuclear aromatics, organic sulfur compounds and phenolic compounds.
8. The process of claim 4 wherein said oil is a petroleum distillate boiling within the range of about 350° to 700° F.
9. A process for refining a lubricating oil stock, which process comprises the steps of contacting said stock with from about 0.1 to 25 weight percent of TIF in the presence of 30 to 300 volume percent of liquid HF, both based on said stock, at a temperature from about 50° to 100° F. for an effective length of time and separating a raffinate phase from an extract phase.
10. The process of claim 9 wherein said contacting is carried out in the presence of from about 10 to 200 volume percent, based on said stock, of an inert diluent.
11. A process for the extraction of aromatic hydrocarbons from a feed that boils below about 450° F. and contains a mixture of aromatic and non-aromatic hydrocarbons, which process comprises contacting said feed with a treating agent consisting of about one mol of thallium fluoride per mol of aromatic to be extracted and sufficient liquid HF to participate in the formation of a complex containing aromatics, TIF and HF and to dissolve said complex, thereby forming an extract phase, separating an upper raffinate phase consisting essentially of hydrocarbons and some HF from said lower extract phase containing liquid HF, complex, and dissolved hydrocarbons, and treating said extract phase to recover the hydrocarbons.
12. The process of claim 11 wherein the amount of liquid HF in said treating agent is between about 10 and 1500 volume percent, based on said feed mixture, and the temperature of contacting is below about 250° F.
13. The process of claim 11 wherein said feed is substantially free of organic-sulfur compounds and phenolic compounds.

14. The process of claim 11 wherein said feed boils below about 325° F. and is substantially free of organic-sulfur compounds and phenolic compounds.

15. A process for the extraction of aromatic hydrocarbons from a feed that boils below about 450° F. and that contains a mixture of aromatic and non-aromatic hydrocarbons and substantially no organic-sulfur compounds and/or phenolic compounds, which process comprises contacting said feed with a treating agent, at a temperature between about -60° F. and about 250° F., separating a raffinate phase, containing a smaller percentage of aromatics than said feed, from an extract phase containing treating agent, aromatics and some non-aromatics, and recovering said hydrocarbons from said extract phase, wherein said treating agent consists essentially of from 10 to 1500 volume percent of liquid HF, based on said feed, and about one mol of TIF per mol of aromatics to be extracted from said feed.

16. The process of claim 15 wherein the amount of liquid HF is from about 100 to 500 volume percent and the amount of TIF is between about 0.1 and the limit of solubility of TIF in said extract phase.

17. The process of claim 15 wherein said extract phase is washed with sufficient diluent hydrocarbon, possessing a boiling point that permits easy separation from said aromatics, to remove substantially all of said non-aromatics from said extract phase, separating a second raffinate consisting of said diluent and said non-aromatics from a second extract phase containing treating agent, said extract aromatics and diluent hydrocarbons and recovering said hydrocarbons from said second extract phase.

18. The process of claim 17 wherein said diluent is pentane.

19. A process for the treatment of a substantially sulfur-free and phenolic-compound free naphtha boiling below about 325° F. and which naphtha consists of benzene, toluene, mixed C₈ aromatics, and non-aromatics and which process comprises intimately contacting said naphtha for from about 5 minutes to 6 hours at a temperature between about 0° and 160° F. with a treating agent consisting of liquid HF, in amount 100 to 500 volume percent based on said naphtha, and TIF, in amount from about 0.8 to 1.2 mols per mol of aromatics in said naphtha, separating a raffinate phase containing non-extracted hydrocarbons from an extract phase containing treating agent, aromatics and some non-aromatics, and recovering said aromatics and non-aromatics from said extract phase.

20. A process for the extraction of aromatic hydrocarbons from a naphtha which boils below 450° F. and contains substantial amounts of organic-sulfur compounds, aromatics and non-aromatics, which process comprises in a first step treating said naphtha to remove substantially all of said organic sulfur compounds without removing substantial amounts of aromatics and contacting said desulfurized naphtha at a temperature below about 250° F. with a treating agent consisting of 100 to 500 volume percent of liquid HF, based on said desulfurized naphtha, and from about 0.1 to 1.2 mols of TIF per mol of aromatic in said desulfurizing naphtha, separating a raffinate phase from an extract phase consisting of treating agent, aromatics and some non-aromatics and recovering said aromatics and non-aromatics from said extract phase.
